UNITED STATES PATENT OFFICE.

CHARLES A. ECK, OF BELLEVILLE, NEW JERSEY.

FAN.

SPECIFICATION forming part of Letters Patent No. 751,484, dated February 9, 1904.

Application filed April 2, 1903. Serial No. 150,802. (No model.)

To all whom it may concern:

Be it known that I, CHARLES A. ECK, a subject of the King of Sweden and Norway, and a resident of Belleville, in the county of Essex and State of New Jersey, have invented certain new and useful Improvements in Fans, of which the following is a specification.

My invention relates generally to fan-motors, and has more particularly reference to means for oscillating the said motor as it rotates.

I shall describe an oscillating fan-motor embodying my invention and afterward point out the novel features in the claims.

15 The object of my invention is to produce an oscillating fan whose action will be positive at all times and one, furthermore, having an adjustment whereby no oscillation will take place unless so desired.

20 A further object resides in constructing the parts so that the fan can be adjusted with relation to the base without interfering with the oscillation of the fan.

To this end my invention comprises the 25 hereinafter-described features of construction and combination of parts.

In the drawings I have embodied my invention in suitable forms, but do not wish to be understood as limiting myself to these particular forms.

30 In the said drawings, Figure 1 is a rear view of a fan embodying my invention with a section through part of the driving mechanism on the line xx of Fig. 2. Fig. 2 is a side view of the fan shown in Fig. 1. Figs. 3 and 4 show modifications.

Similar letters of reference indicate corresponding parts in the different views.

40 A indicates a fan-motor of any suitable construction, but preferably adjustably secured on the hollow base B by suitable means, as the socket b', carried by the said base and the corresponding ball a', forming together a joint by means of which the fan can be tipped or 45 adjusted to different positions at an angle to the base. This said base B is split, as at b'', and provided with the tightening device b''' to hold the fan securely after it has been adjusted to the desired position.

50 The ball a' is provided with an extension a'',

the said ball and extension being provided with a vertical passage a³, formed with a seat a⁴. Resting upon the balls a⁵ in this seat is a hollow spindle a⁶, carrying the fan-motor A, which in this way is mounted to turn.

55 The fan-motor carries upon its armature-shaft a⁷ a worm a⁸, engaging with the worm-wheel a⁹. Mounted in the bearing a¹⁰ is a shaft a¹¹ at right angles to the armature-shaft. Upon this shaft is located a disk a¹², carrying a bushing a¹³ and provided with a slot a¹⁴, open at one end a¹⁵. The worm-wheel a⁹ is mounted in the bushing a¹³ and is interposed between two very thin insulation disks a¹⁶ and a¹⁷, made, preferably, of vulcanized fiber material, which, with the worm-wheel, are held up against the slotted disk a¹² by means of the springs a¹⁸ on the bushing a¹³, the resultant friction being sufficient to rotate the disk a¹² 65 with the worm-wheel a⁹. Mounted in the framework of the motor and upon the pin a¹⁹ is a segment a²⁰, provided with an arm a²¹ and engaging with a spiral a²², fixed to the extension a² of the ball a' by means of the screw a²⁰, so that the said spiral is fixed with the base. The 70 arm a²¹ carries a pin a²⁵, entering the slot a²⁶, having an aperture a²⁷, of the rod a²⁸, which is loosely connected with a block a²⁴ at its other end, which in turn is adjustable in the slot a¹⁴ by means of the screw a²⁹ and holes a³¹. From 75 this it will be understood that the rotation of the armature-shaft a⁷ causes the worm a⁸ to impart its motion to the worm-wheel a⁹, which in turn by friction rotates the disk a¹², thereby causing the segment a²⁰ to oscillate the fan-motor by engaging with the fixed spiral a²². By adjusting the position of the block a²⁴ the distance of the oscillation can be varied, or the 80 oscillation can be entirely obviated by moving the block a²⁴ to the center of the disk a¹².

The speed of the oscillation will of course depend on the speed of the rotation of the fan-motor. In case the block a²⁴ is placed central of the disk a¹², as noted above, the rotation of the worm-gear and disk will of course continue, though no oscillation will take place, and in case the fan-motor should by accident encounter any obstruction as it turns from side to side the result would not in any way stop the rotation of the motor or disturb the 90 95 100

operating parts, as the worm-wheel would continue to rotate, while the disk a^{12} would remain stationary, owing to the fact that the said disk is operated by friction only. The 5 motor is thus oscillated positively by the means set forth, which are operated by the rotation of the armature-shaft, and the oscillating means except the fixed gear on the ball a' oscillate with the fan-motor. In order 10 that the wiring may not interfere with the proper operation of the means of oscillating the fan, the wires C are carried up through the hollow base B, through the passage a^3 , hollow spindle a^6 , through the opening a^{26} in 15 the latter, and through the passage a^{27} to the field-coils c' .

In Fig. 3 is shown a modification in which I employ a rack a^{28} and pinion a^{29} in place of the spiral and segment shown in Fig. 2. In 20 Fig. 4 I have shown still another modification in which I employ a bevel-gear a^{30} and a bevel-segment a^{31} .

Other modifications could of course be used.

When it is desired to have a non-oscillating 25 fan and to adjust the fan-motor around its axis with relation to the base, the pin a^{55} is disengaged from the aperture a^{57} and allowed to rest loosely in the slot a^{56} , the block a^{24} having previously been placed central of the disk 30 a^{12} , as hereinbefore explained. This permits the fan-motor to be adjusted by turning the spindle a^6 , which is then secured in position by the screw a^{58} . When it is desired to have the fan oscillate again, the screw a^{58} is loosened 35 and the block a^{24} moved away from the center of the disk a^{12} . The action of the motor will then move the rod a^{23} until the pin a^{55} enters the aperture a^{57} , when the motor will commence to oscillate again.

40 Having thus described my invention, what I claim is—

1. The combination with a base, of a fan-motor, a spindle mounted to turn on the base carrying the said motor, an armature-shaft on 45 said motor, a worm carried by the same, a worm-wheel engaging with said worm, a gear stationary with the base, a gear moving with the fan-motor engaging with the first-mentioned gear, a friction-disk moving with the 50 worm-wheel, and a rod connecting the friction-disk with the gear moving with the motor, whereby the rotation of the armature-shaft causes the spindle carrying the fan-motor to oscillate.

55 2. The combination with a base, of a fan-motor, a spindle mounted to turn on the base carrying the said motor, an armature-shaft on

said motor, a worm carried by the same, a worm-wheel engaging with said worm, a spiral stationary with the base, a segment moving with the fan-motor engaging with the spiral, a friction-disk moving with the worm-wheel, and a rod connecting the friction-disk with the segment, whereby the rotation of the armature-shaft causes the spindle carrying the fan-motor to oscillate. 60

3. The combination with a base, a fan-motor, a spindle mounted to turn on the base carrying the said motor, an armature-shaft on 70 said motor, a worm carried by the same, a worm-wheel engaging with said worm, a gear stationary with the base, a gear moving with the fan-motor engaging with the first-mentioned gear, a friction-disk moving with the worm-wheel, and a rod connecting the friction-disk with the gear moving with the motor and adjustably secured to the said friction-disk, whereby the rotation of the armature-shaft causes the spindle carrying the fan-motor to oscillate. 75

4. The combination with a base, of a fan-motor mounted to turn upon the said base, an armature-shaft carried by the motor, and means for oscillating the said motor with relation to the base comprising in part: a worm 85 carried by the armature-shaft, a shaft located at right angles to the armature-shaft, a friction-disk having a bushing on said shaft, a worm-wheel and two insulation-disks between which latter it is interposed on said bushing, 90 the worm-wheel engaging with the worm aforesaid, and springs on said bushing for keeping the worm-wheel and composition disks in contact with the friction-disk whereby the said friction-disk moves with the worm-wheel. 95

5. The combination with a base and fan-motor having an armature-shaft and mounted to turn with relation to the base, of means for oscillating the said fan-motor from the armature-shaft of same comprising: a gear fixed 100 with relation to the base, a segment engaging with the same mounted on the fan-motor, an arm and a pin on the segment, a rod having a slot with an aperture for the reception of the pin of the segment, and gearing connecting said rod with the armature-shaft of the motor. 105

Signed at Belleville this 17th day of March, 1903.
